CLAIM

The ornamental design for a golf putting cup, as shown and described.

DESCRIPTION

FIG. 1 is a perspective view of the golf putting cup showing the claimed design;

FIG. 2 is a top view thereof;

FIG. 3 is a bottom view thereof;

FIG. 4 is a right view thereof;

FIG. 5 is a front view thereof;

FIG. 6 is a left view thereof; and,

FIG. 7 is a back view thereof.

The Broken lines in the figures show portions of the golf putting cup that form no part of the claimed design. The broken lines illustrating a flag in FIGS. 1-7 represent environmental subject matter and form no part of the claimed design.

1 Claim, 7 Drawing Sheets
